**SIGNATURE STACKER AND TRANSFER DEVICE
FOR PRINTING PRESS OUTFEED**

Otho Kile, Homewood, and Robert G. Treptow, Park Forest, Ill., assignors to R. R. Donnelley & Sons Company, a corporation of Delaware

Application March 22, 1957, Serial No. 648,477

27 Claims. (Cl. 271—88)

This invention relates to a signature stacker and transfer device for the outfeed of a printing press.

The principal object of the present invention is to provide a compact and dependable device which is adapted to receive signatures coming from a printing press and continuously arrange them in "lifts" of convenient size for manual transportation from the stacker.

A further object of the invention is to provide such a machine in which the signatures of each lift are jogged into registration as the lift is formed.

A further object of the invention is to provide such a machine in which two carriages are mounted for horizontal movement between a loading area and an unloading area, and in which each transfer carriage is provided with a signature supporting platform which may move down as a lift of signatures is formed on it at the loading area, and which returns to an elevated position after the carriage is at the unloading position.

A further object of the invention is to provide such a machine in which the movement of the carriages and the movement of the platforms on the carriages is entirely automatic, so that the two carriages may alternate between loading and unloading positions to continuously handle signatures fed to the machine.

Yet another object of the invention is to provide such a machine in which signatures coming from a printing press in shingled relationship are first formed into a temporary pile at a signature-receiving station, and in which the temporary pile is then transferred from the receiving station to a platform in the loading area by a rocking stacker arm.

Yet another object of the invention is to provide a machine in which the entire drive for all components may be distributed from a single input shaft.

The invention is illustrated in a preferred embodiment in the accompanying drawings in which:

Fig. 1 is a plan view of a machine constructed in accordance with the invention;

Fig. 2 is a side elevational view of such a machine;

Fig. 3 is a fragmentary plan view on an enlarged scale of the machine infeed and signature-receiving station;

Fig. 21 is a diagrammatic, or schematic view of the device including particularly the transfer carriages and platforms and the direct driving mechanisms for the carriages and platforms;

Fig. 22 is a schematic illustration of the drive mechanism; and

Fig. 23 is an electric wiring diagram of the control circuits.

Machine generally

Referring to the drawings in greater detail, and referring first to Figs. 1, 2, 21 and 22, the present machine consists generally of a frame A on which is a power distributing system B (Fig. 22). Driven in various ways from power system B are:

35 A signature infeed conveyor C which conveys signatures from a press outfeed to a delivery table in a signature-receiving station C1; movable elements in the signature-receiving station; a pair of transfer carriages D1 and D2 which are mounted for horizontal reciprocation on the frame A so that at any given time one carriage is in a loading area 25 adjacent the signature-receiving station while the other platform is in an unloading area 26 more remote from the signature-receiving station; and the vertically reciprocable platforms on the carriages.

45 Raising and lowering of the carriage platforms is effected from system B through a cam actuated pulley system, indicated generally at E (Fig. 21); while the reciprocation of the carriages C1 and C2 is accomplished by a reversing drive indicated generally at F in Fig. 21.

50 Transfer of the signatures in small, temporary stacks from the receiving station B1 to the platform of a carriage in the loading area is accomplished by a stacker arm mechanism G which is also actuated and controlled from power system B; while the jogging of signatures on the platform into perfect register and the control of signatures in a stack is accomplished by a stack control and jogger mechanism H. Finally, the operation of the entire device is controlled by suitable electric circuitry including various switches actuated by movement of the carriages or the

55 platforms during the normal operation of the machine. The electric control system is seen in Fig. 23, and is indicated by the letter I.

Machine frame A

65 Referring to the drawings in greater detail, and referring first to Figs. 1 and 2, the machine frame A includes a base platform 27 which is seen in Fig. 2 to have at its left-hand end an upright infeed supporting frame work 28 on which one end of a forward infeed frame 29 is supported. Extending upwardly from the frame work 28

70 is a bridge frame 30 which carries some of the feed and feed control components by means of which signatures

are formed into a temporary stack in the receiving station C1, which occupies the area beneath the bridge frame.

To the right of the receiving station C1 as seen in Fig. 2, is the loading area 25 which is flanked on its two sides by a stack control side frame 31 and a jogger side frame 32 (see Fig. 1). Still further to the right in Fig. 2 is the unloading area 26, and between the loading area 25 and the unloading area 26 is a control bridge frame indicated generally at 33.

Power distributing system B

The power distributing system B is shown schematically in Fig. 22 and various parts appear in Figs. 3 to 7. It includes a main drive shaft 34 which extends transversely of the machine between the infeed frame members 28, and has at one end a main input sprocket 35 over which is trained an input chain 35a by means of which the shaft 34 is driven from a sprocket 36, operation of which is controlled by standard solenoid clutch and brake units 36a and 36b (Fig. 3). Commonly a bank of sheet stackers are arranged in a line at the outfeed of a bank of printing presses, and a single longitudinal main power shaft P is provided from which all of the signature stacker mechanisms are selectively powered. A gear P1 on shaft P meshes with a gear 36c on the input side of clutch 36a. Where a single stacker is to be used the gear 36c may mesh directly with a drive gear on the shaft of an electric motor.

On the main drive shaft 34 adjacent the input sprocket 35 is a small infeed drive sprocket 37 carrying an infeed drive chain 37a for driving the infeed C through a sprocket 38 on an infeed drive shaft 38a which is journaled in the infeed frame 29. At the end of the main drive shaft 34 opposite the sprocket 35 is a power distributing gear 39 from which power passes through a pair of idler gears 40 and 41 to a stub shaft 42. A sprocket 43 on shaft 42 carries a receiving station cam control chain 44 for operating the receiving station components C1 through a sprocket 45 on a delivery table cam shaft 46 which is supported in the bridge frame 30. Chain 44 is tensioned by an idler sprocket 44a. (See Fig. 4).

Approximately at the center of the main drive shaft 34 is a bevel gear 47 which meshes with a bevel gear 48 on a longitudinal stub shaft 49 which also carries a cam control distributing gear 50. At one side of cam control distributing gear 50 is a longitudinal cam shaft 51 for the stack control cams; and cam shaft 51 is driven by a gear 51a meshing with gear 50.

Drive for platform operating mechanism E is through a longitudinal shaft 52 which is normally in operative engagement with a coaxial shaft 52a through a single tooth clutch 52b, shaft 52a in turn being driven from cam shaft 51 through intermeshing gears 51b and 52c. From clutch shaft 52 power is transmitted through intermeshing gears 52d and 53a to a shaft 53, thence through a gear 53b to a gear reducer input gear 54a on input shaft 54b of a gear reducer 54. Raising and lowering of the platforms is accomplished by mechanism operated from a gear reducer output shaft 54c, as will be described hereinafter.

On the opposite side of the cam control distributing gear 50 is a jogger cam shaft drive gear 55 which is mounted on a cam shaft 56 to control the operation of the jogger mechanism H.

As previously stated, movement of the transfer carriages B1 and B2 is accomplished by the reversing drive F, and the input for the reversing drive F is from a gear 57 on the same stub shaft 42 which drives the receiving station control cams. The accomplishment of the reversing drive from gear 57 will be described in detail in connection with the reversing mechanism F.

Operation of the stacker arm mechanism G is obtained in one aspect by means of a pair of conjugate cams mounted on the stub shaft 42, which will be described in more detail hereinafter, while control of the gripping of temporary stacks of signatures by the stacker arm mech-

anism G is accomplished from a jaw control drive sprocket 58 on the main shaft 34 which acts through a jaw control chain 59 to drive a sprocket 60 on a jaw control cam shaft 61, about which the main sheet transfer arm of the stacker arm mechanism G is pivotal for its feeding movement.

Infeed mechanism C

The infeed mechanism C of the present device is adapted to take signatures which are fed in shingled relationship by a sheet or signature feed device S (Fig. 2) which takes them away from the printing press outfeed, and includes a series of driven parallel feed tapes 62 which are wrapped nearly around drive pulleys 63 on the shaft 38a, around a tensioning pulley 64, and around receiving pulleys 65 on a receiving shaft 66. There are also suitable supporting rollers 67 which are mounted at intervals in the infeed frame 29.

Referring to Figs. 4 to 6 at the inner end of the infeed C and the entrance to the signature-receiving station C1 the tapes 62 pass over feed pulleys 68, and the folded edges of the signatures on the tapes ride under a weighted creasing roller 69 which is mounted on an arm 70 journaled on a cross shaft 71 in the bridge frame 30 to crease the folds. After passing over pulleys 68 the tapes traverse pulleys 73 on a shaft 74 at the entrance to the receiving station, thence around on pulleys 75 on a shaft 76 at the receiving station outfeed end and back to the drive pulleys 63.

At the entrance to the receiving station the signatures are centered between tapering side guides 77 of a delivery table 78 which has spaced longitudinal plates 78a flanking the tapes 62, and which has bosses 79 at its rear end by means of which it is rockably supported on shaft 74. At its extreme inner end (the outfeed end of the receiving station) the delivery table 78 has three, spaced upstanding lips 80 against which the piled up signatures are arrested in the form of a temporary pile, ready to be picked up by the stacker arm mechanism G and placed upon the platform of carriage D1, which is in the loading area 25 as seen in the drawings.

To pile up the signatures entering the receiving station C1 are bearer rollers 81 which overlie tape pulleys 73 and are carried on bifurcated arms 82 on cross shaft 71. A cross bar 85 which is journaled in side spurs of bridge frame 30 carries a rocking feed brake arm 86 which has a signature brake shoe 87 generally in line with bearer rollers 81 and overlying a brake anvil 87a on the delivery table 78. The bearer roller arms 82 are also provided with weight arms 88 carrying longitudinally movable weights 89 for adjusting the pressure of the bearer rollers 81.

Operation of the delivery table 78 and rocking feed stop arm 86 is controlled by means of two cams, numbered respectively 90 and 91, on shaft 46. For this purpose, delivery table 78 has an upstanding cam arm 92 with a follower roller 92a which rides on top of cam 90, while stop arm 86 has a follower roller 86a which is held in contact with the bottom of cam 91 by means of a follower spring 86b. Cams 90 and 91 are so phased that as the outfeed end of delivery table 78 drops, brake shoe 87 is lowered against anvil 87a to hold signatures which are not in position to be positively gripped by stacker mechanism G. Thus, these movements are coordinated with the movements of the stacker arm mechanism, as will be described.

Transfer carriages D1 and D2

As seen in Figs. 1 and 2, and also in Figs. 13 to 16, the transfer carriages are shown with the carriage designated D1 in the loading area 25, while the transfer carriage D2 is in the unloading area 26; although these carriages periodically reverse their positions as the machine operates. As best seen in Fig. 15, the transfer carriage D2 is mounted for rolling movement on a longi-

tudinal monorail 92 which is positioned on the left side of the base frame member 27, as viewed in Fig. 15. Rail 92 has a longitudinal central track groove 93, and an overhanging guide 94 which is opposed by a base portion 95; while the carriage D2 has a truck base 96 having rollers 97 received in the track groove 93, and also top and bottom guide rollers 98 and 99 which are positioned, respectively, below the overhang 94 and above the base portion 95 of the monorail 92. A gib plate 100 and a removable rib 101 provide bearing surfaces for the stabilizing rollers 98 and 99, respectively, and prevent any substantial lateral instability of the transfer carriage D2.

Extending upwardly from the truck base 96 of the transfer carriage D2 is an upright guide rail 102 which is seen in Fig. 16 to have vertical guide grooves 103, 104 and 105 in three of its sides to receive suitable guide rollers 106, 107, and 108 on a vertically reciprocable carriage 109 to which is secured a transfer platform 110. The transfer platform 110 is seen in Fig. 15 to be inclined to the left, which is away from the jogger elements of mechanism H, so that the jogging action performed upon a stack of sheets or signatures on the transfer platform 110 piles them up against the left hand side where they are held beneath the stack control portion of mechanism H; and the platform has recesses on its two longitudinal margins to facilitate moving a stack, or "lift" of signatures from the platform.

As best seen in Figs. 13 and 15, transfer carriage D2 has at the upper end of the vertical guide rail 102 a bracket 111 to receive the top pulleys of a compound pulley system indicated generally at 112, around which is trained a supporting and elevating cable 113 for the carriage 109 and platform 110.

Platform elevating drive E

Actuation of the compound pulley system 112 is by means of an operating cable 114, the path of which may best be seen in Fig. 21. Transfer carriage D2 must move fore and aft of the machine along the track 92, so to use a cable system it is necessary to provide a compensating linkage consisting of a carriage link 115 which is pivotally connected to the carriage truck 96 at 116, and a connecting link 117 which is pivoted to the link 115 at 118 and to the base frame member 27 at 119. The actuating cable 114 passes down around a pulley 120 which is coaxial with the pivot 116, up along the link 115 and around a pulley 121 which is coaxial with the pivot 118, thence downwardly along the link 117 and around a pulley 122 which is coaxial with the pivot 119. Thus the total distance between the pulleys 120 and 122, as traversed by the actuating cable 114, remains constant during movement of the transfer carriage D2. From the pulley 122 the actuating cable 114 passes around a pair of horizontally positioned pulleys 123 and 124, thence around a pulley 125 which is mounted on a pivoted, inclined bracket 126, and the cable is anchored at the lower end of a cam follower arm 127 which is pivoted on a cross shaft 128 mounted in bosses 129a of a bracket 129 which is between gear reducer 54 and gear 53b. The follower arm 127 has a follower which is held against a cam 130 on the left-hand end of gear box output shaft 54c by the weight of platform 110. However, when platform 110 is latched at the top of guideway 102, a tension spring 131, which connects pivoted bracket 126 with an upright bracket 27a of base frame 27 (Figs. 14 and 17) keeps tension on the cable 114.

Movement of the transfer carriage D2 is effected by means of a fixed actuating arm 132 which extends longitudinally from a bracket 133 on the carriage and has its free end secured to a drive chain 134 one end of which is trained around a horizontally disposed sprocket 135 the spindle 136 for which is mounted on the central up-

right bracket 27a. At its other end the drive chain 134 is trained around a sprocket 137 which is mounted on an upright clutch shaft 138 and is associated with the reversing drive F. Thus, movement of the chain 134 clockwise around sprocket 135 as seen in Fig. 17 moves the transfer carriage D2 from the unloading station 26 to the loading station 25, while movement of the chain 134 in the opposite direction returns the carriage D2 from the loading station to the unloading station; and this reversing movement of the chain 134 is accomplished by the reversing drive which is taken off the gear 57 seen in Fig. 22.

The construction and operation of the transfer carriage D1 is precisely like that of the transfer carriage D2 heretofore described, except that the monorail track 92a upon which the carriage travels is on the opposite side of the base frame 25 facing in the opposite direction, and the carriage D1, correspondingly, is on the opposite side of the base frame 25 from the carriage D2 as seen in Fig. 14. Thus, there is no detailed description of all the components of the transfer carriage D1, but the components are numbered in the drawings with numerals identical with those of the transfer carriage D2 but with the suffix *a* appended to each reference numeral.

Reference to Figs. 13, 17 and 21, in particular, shows clearly the function of the compensating links 115 and 117 of carriage D2 and 115a and 117a of carriage D1, which permit the use of a pulley lift system for the platform 110 and 110a in conjunction with moving carriages 30 on which the platforms are mounted.

As best seen in Figs. 13 and 21, the upright guideway 102 of the transfer carriage D2 is provided at its upper end with a spring loaded latch 139 which is adapted to engage a portion of the platform elevating carriage 109 when the carriage reaches its most elevated position. The carriage D1 has a similar latch 139a. The latches 139 and 139a are provided with suitably angular forward camming faces which are adapted to contact actuating pins, numbered 140 and 140a, respectively, on the bridge frame 33, so that as each transfer carriage moves toward the loading area 25 its platform is automatically disengaged by the latch which is holding it, to permit the platform to descend as it is loaded with temporary stacks of sheets or signatures taken from the receiving station C1.

Reversing drive F for carriages

As previously stated, the reversing drive F for carriages D1 and D2 is powered by gear 57 on stub shaft 50, which operates to obtain reversing motion of the sprocket 137 for the carriage drive chain 134, and for the similar sprocket 137a for the carriage drive chain 134a for the carriage B1.

As best seen in Figs. 5, 7, 8, 19 and 20, the driving connection between gear 57 on shaft 42 and sprockets 137 and 137a is obtained by meshing with gear 57 a gear 141 on a shaft 142 which extends into a crank and gear segment box 143. Within the box 143 there is mounted on the crankshaft 142 a crank 144, and a gear segment 145 is pivotally mounted on a pin 146 in the wall of the gear segment box 143, so that the segment is opposite the end of shaft 142. The gear segment 145 is provided with a slot 147 to receive a crank slider 148 which is actuated by means of a crank pin 149 on crank 144, so that rotation of crankshaft 142 produces a reciprocating action of the gear segment 145.

A miter gear shaft 150 which extends transversely through the box 143 and projects both ways therefrom has a pinion 150a in mesh with gear segment 145, so the shaft 150 is rotated alternately first in one direction and then in the other direction. As seen in Fig. 7, miter gear shaft 150 has at one end a miter gear 151 and at the other end a miter gear 151a which provide the drives, respectively, for the sprockets 137 and 137a. Meshing with miter gears 151 and 151a, respectively, are

miter gears 152 and 152a, which are positioned at the upper ends of clutch drive shafts 153 and 153a, respectively, which are supported in rings 154 and 154a in vertical axial alignment with the clutch shafts 138 and 138a, respectively. The clutch drive shafts 153 and 153a are provided at their lower ends, respectively, with radially extending clutch drive arms 155 and 155a which have depending clutch drive fingers 156 and 156a, respectively.

As best seen in Figs. 19 and 20, mounted on shafts 138 and 138a above the sprockets 137 and 137a are two-way solenoid clutch mechanisms, indicated generally at 157 and 157a, respectively, which are identical; and accordingly only the mechanism 157 will be described in detail while similar reference numerals will be applied to the similar parts of mechanism 157a, with the letter *a* added to the reference designation. The two-way solenoid clutch mechanism 157 includes a top plate 158 which is clamped onto clutch shaft 138, and mounted on the underside of the plate 158 is a pair of rotary solenoids 159 and 160 which have their shafts 161 and 162, respectively, extending upwardly through holes in the plate 58. An upright pivot pin 163 surmounting plate 158 adjacent rotary solenoid spindle 161 supports a swingable clutch finger 164 which is connected by a link 165 to the solenoid 160. Also mounted on top of plate 158 is a pivot pin 166 for a swingable clutch finger 167 which is connected by a link 168 to shaft 161 of rotary solenoid 159. In order that the clutch mechanism 157 may assume a normal, at rest position, the plate 158 is provided with a detent notch 169 to receive a spring loaded detent 170 which is mounted on a suitable bracket on the frame. As seen in Figs. 19 and 20, the clutch fingers 164 and 167 occupy a normal, at rest position with their outer ends inside the periphery of the plate 158, and the clutch drive finger 156 is so positioned that either of the clutch fingers may be moved by its actuating rotary solenoid to a more outward driving position where its outer end is in the path of the clutch drive finger 156. Since the clutch drive shaft 154 reverses its direction of rotation cyclically due to the driving action of the crank 144 and gear segment 145, the clutch drive finger 156 may drive the solenoid clutch mechanism 157 and associated sprocket 137 clockwise as seen in Fig. 19 to move the carriage D2 into loading position by engagement with clutch finger 164, or may drive sprocket 137 counterclockwise by engagement with clutch finger 167 to return the carriage D2 to unloading position.

The clutch member 157a is identical with clutch mechanism 157 but is positioned 180° out of phase with said mechanism 157 to prevent interference between them. Engagement of clutch drive finger 156a with clutch finger 164a rotates clutch mechanism 157a clockwise to move carriage D1 to unloading position; while conversely, engagement of drive finger 156a with clutch finger 167a rotates clutch mechanism 157a counterclockwise to move carriage D1 to loading position.

Actuation of both of the reversing clutch mechanisms of the reversing carriage drive F is effected at suitable times in the machine cycle by the control mechanism I, which will be described hereafter.

Stacker arm mechanism G

The stacker arm mechanism G is best seen in Figs. 5, 6, 9 and 10, and its principal components include a generally upright rocking stacker arm 171 which is pivoted at its lower end on shaft 61, and a movable gripping jaw mechanism 172 which is mounted at the top of stacker arm 171. The function of the stacker arm 171 is to rock between a stack pick-up position as seen in the drawings, where the gripping jaws 172 are between the stop members 80 of delivery table 78 in the receiving station C1 so it may pick-up a temporary stack of signatures from the delivery table, to a release position in which its upper

end is adjacent bridge frame 33 so that the gripping jaw mechanism 172 may release a temporary stack of sheets which drop onto the platform of the carriage at the loading position.

Reciprocating swinging movement of stacker arm 171 is provided by means of a pair of conjugate cams 173 and 174 which are mounted on shaft 42 just inside gear 41, as seen in Fig. 7. Referring to Fig. 6, on a pivot 175 in upright infeed frame 28 is a bell crank, indicated generally at 176, which has an upright arm 177 provided with a cam follower 178 engaging the surface of cam 173, and a generally horizontal arm 179 provided with a cam follower 179a, which rides on the surface of cam 174. At the lower end of bell crank arm 177 is a turnbuckle link 180 which connects the bell crank with a cross member 171a (Fig. 10) of rocking delivery arm 171 to impart the desired rocking motion to it in phase with the rotation of shaft 42.

Actuation of the gripping jaws 172 at the top of the rocking stacker arm 171 is controlled by means of a cam 181 on shaft 61 which, as previously mentioned, is driven by jaw control cam drive sprocket 60 (see Fig. 22). Cam 181 controls the movement of a cam follower lever 182 which is pivotally mounted at 183 on stacker arm 171 and has a follower roller 184 urged against the surface of cam 181 by a follower spring 182a. Cam follower lever 182 acts through a suitable spring loaded, adjustable link 185 to open and close the gripping jaws 172 in timed relationship with the swinging movement of stacker arm 171. Thus, as the arm 171 approaches the position seen in Fig. 6, the jaws 172 start to close, and ultimately do close upon the forward margins of a temporary stack of signatures which is abutted against the stop members 80. The jaws remain closed while the stacker arm 171 swings to its discharging position with its upper end adjacent bridge frame 33, and the jaws then open to release the temporary stack of signatures which drop onto the platform 110a.

Cooperating with the stacker arm 171 and jaws 172 to properly control the signatures during delivery is a combined longitudinal jogger arm and stack support member 186. Although this is part of the jogging mechanism, it is also an important component of the mechanism for removing temporary stacks of signatures from the receiving station to the platform which is in the loading area, so that its operation will be described at this point.

As seen in Figs. 6 and 7, the combined jogger and stack support 186 includes a pair of aligned upright arms 187 which are parts of bell cranks pivotally mounted on pins 188 in suitable brackets 189 which are mounted on the base frame member 27 almost directly below the stop members 80 of delivery table 78. The arms 187 are connected at their upper ends by a cross member 190, and at the ends of member 190 are spring thrust plates 191 to receive the thrust of compression springs 192 which are mounted on spring guides 192a at the sides of upright frame member 28. The bell cranks of which arms 187 are a part also have cam follower arms 193 at the outer ends of which are follower rollers 194 which are urged into engagement with the surface of a pair of cams 195 which are seen in Fig. 5 to be mounted near the ends of main power distributing shaft 34. Construction of cam 195 is such that the upper end of the combined jogger and stack support member 186 rocks in timed relationship with the operation of stacker arm 171, so that during the transfer of a temporary stack of signatures by the stacker arm 171 an overhanging stack supporting lip 196 atop member 186 occupies the position shown in Fig. 6 where the stack of signatures gripped by the jaws 172 may slide across the support member. As the jaws 172 are opened to release the temporary stack, the stack support member 186 is pivoted to move its stack supporting lip 196 away from the jaws 172 so that both ends of the stack are released at effectively

the same time in order to cause the stacks to drop horizontally upon the platform.

Also cooperating with the stacker arm and stack support member are the delivery table 78, and the signature stop member or brake 87, both of which are controlled respectively, by the cams 90 and 91 as heretofore described. The cams 90 and 91 are so phased that as the gripping jaws 172 of the stacker arm 171 close on a temporary stack of signatures on the delivery table, the cam 90 pivots the table downwardly about the shaft 74 on which its rear end is mounted so as to drop the stop members 80 out of the way of the temporary stack to permit its removal by the stacker arm 171. Simultaneously, as previously pointed out, the signature brake shoe 87 is moved against anvil 87a by cam 91 so as to hold any signatures not actually gripped by stacker arm jaws 172 until the temporary stack is removed and the delivery table has again assumed a horizontal position. The anvil is seen in Fig. 5 to be above infeed belt level, so that signatures forward of the anvil are out of the grip of brake shoe 87, but may be gripped by jaws 172.

The stack supporting lip 196 is positioned surmounting a transversely extending jogger plate 198 which is supported on the cross piece 190 by means of a bracket 198a. After a temporary stack of signatures is dropped onto the platform, cams 195 cause the member 186 to rock back and forth a number of times on its pivots and push the signatures in a temporary stack toward stops 33a which are hung from bridge frame 33 at the opposite end of the platform so as to bring the signatures into longitudinal registration.

Jogger and stack control mechanism H

The jogger and stack control mechanism H is best seen in Figs. 9 to 12, inclusive, and consists generally of jogger members 199 which are on the side of the machine opposite the stacker arm 171, and a stack control mechanism 200 which is opposite the jogger arm mechanism. It will be recalled that the platforms 110 and 110a of the transfer carriages D1 and D2, respectively, are both laterally inclined, and this incline is in the direction of the stack control mechanism 200, so that the operation of the jogger mechanism 199 pushes the stacks down the incline where they may be held down by the action of the stack control mechanism as will be described.

The jogger mechanism 199 includes a jogger arm supporting shaft 201 mounted on a suitable bracket 202 on the base frame 27. A side jogger member, indicated generally at 203, includes a bushing 204 by means of which it is rockable on shaft 201; and extending upwardly from bushing 204 is a pair of spaced upstanding jogger arms 205 surmounted by a jogger bracket 206 on which a jogger plate 207 is adjustably mounted. Extending horizontally from bushing 204 the jogger member 203 has a cam arm 208 provided with a cam follower 209 which is urged against a cam 210 on jogger cam shaft 56 by a jogger cam spring 211. Thus, rotation of the cam 210 reciprocates the jogger plate 207 laterally in timed relationship with the operation of the stacker arm 171 and associated stack feeding components. A frame side plate 212 adjacent the jogger arms 205 is provided with a pair of jogger cushioning springs 213 which bear against spring brackets 214 on the arms 205 to cushion the movement of the jogger; and opposite the jogger plate 207 are spaced, fixed side plates 215 against which the signatures are jogged.

The stack control mechanism 200 includes two coordinated finger sets, each containing three vertically slideable fingers mounted in carrier arms which may rock laterally in and out between side plates 215 so as to carry the vertically slideable fingers into or out of engagement with the top of a stack of signatures on the platform in the loading area. Movement of the two sets of fingers is coordinated with the operation of stacker arm

171; and at least one set is engaged with the stack at all times.

As best seen in Fig. 9, rockably mounted on shaft 56 are three finger arms 216 connected by a tie bar 216a, and paired with them are three finger arms 217 connected by a tie bar 217a. The arms 216 and 217 have sleeves 218 and 219, respectively, which respectively slidably carry finger shafts 220 and 221 which have brackets 222 and 223, respectively, at their upper ends carrying thin, overhanging fingers 224 and 225, respectively, which are adapted to overlie the adjacent margin of the stack of signatures on the platform in the loading area. Vertical movement of the three finger shafts 220 is provided by three lift arms 226 which are pinned to the bottoms of shafts 220 and connected at their lower ends to finger lift levers 227 which are pinned to a rocking shaft 228 adjacent jogger arm shaft 201, so that they move together to raise and lower fingers 224 simultaneously. Pivotedly mounted on shaft 228 are lift levers 229 which actuate two lift arms 230 and a lift and detector arm 230a for the finger shafts 221. The two lift arms 230 and the arm 230a are joined by a connector plate 231.

As seen in Fig. 12, mounted on cam shaft 51 is a pair of lifting cams 232 bearing on which are cam rollers 233 of lift levers 227 to control the vertical movements of the three finger shafts 220. Also on shaft 51 is a pair of lifting cams 234 bearing on which are cam rollers 235 of lift levers 229 to control vertical movement of finger shafts 221.

Rocking movement of the finger arms 216 is provided by a rocker arm 236 which has a tension spring 237 to hold a cam roller 238 in contact with a finger arm rocker cam 239. Similarly, finger arms 217 are rocked by a rocker arm 240 which has a tension spring 241 holding a cam roller 242 in contact with a rocker cam 243 which is 180° out of phase with cam 239.

The lifting cams 232 and 234 and the rocker cams 239 and 243 are so arranged and coordinated with stacker arm 171 that one of the two finger arms 216 or 217 rocks to carry its finger set out of contact with the growing stack just before the stacker arm drops another temporary stack onto it. The fingers of this set are lifted and brought to a position above the top of the stack including the added temporary stack.

At this time the longitudinal jogging by member 186 and lateral jogging by mechanism 199 takes place to jog the newly added temporary stack into register with the previously jogged parts of the lift. Then the lifted fingers are dropped onto the lift including the newly jogged temporary stack, to press air out from between the signatures, crimp the signature folds to make the lift level on top, compress the stack, and hold the jogged signatures in place. The other finger arm then rocks out to pull its fingers from under the added temporary stack, and those fingers are lifted and dropped back onto the top of the stack while the stacker arm is going back for the next temporary stack.

An air manifold 197 (Figs. 2 and 9), on side frame 31, directs a stream of air against the folded margins of the temporary stack in order to facilitate the jogging action.

Machine control I

Control of machine operation is provided through the electrical control system illustrated in Fig. 23, the locations of the various operating switches being shown in Fig. 21.

Surmounting control bridge frame 33 is a control panel and relay box 250 on which are located a "stop" button 251, a "run" button 252 which is pressed to initiate normal machine operation and an "inch" button 253 which is used when it is necessary to "inch" the machine while adjusting it or clearing jammed signatures.

As seen in Fig. 21, control bridge frame 33 carries on its upright arms four normally open microswitches: 254 and 255 on a lower level, and 256 and 257 on a higher

level; numbers 254 and 257 being associated with carriage D1, and 255 and 256 with D2. In addition, surmounting the bridge frame are normally closed microswitches 258 and 260, associated respectively with D2 and D1; while adjacent the unloading station are a normally closed D2 microswitch 259 and a normally closed D1 microswitch 261. Finally, at the base of control bridge frame 33, where it may be actuated by the outermost stack control finger lift arm; shown as 230a in Figs. 9 and 12, is a platform retard switch 262. The switches 254 to 261 control the carriage drive clutch solenoids to move the carriages in and out; while a normally open retard switch 262 controls the engagement of single point clutch 52b through a solenoid 263 to cut out the platform drive E when the platform at the loading area descends too rapidly for the rate of delivery of signatures to it.

Normally open switch 254 and normally closed switch 261 act through a relay 264 to control rotary solenoid 159a; normally open switch 255 and normally closed switch 259 act through a relay 265 to control rotary solenoid 159; normally open switch 256 and normally closed switch 260 act through a relay 266 to control rotary solenoid 160a; while normally open switch 257 and normally closed switch 258 act through a relay 267 to control rotary solenoid 160.

Assuming the carriages D1 and D2 in the positions shown in the drawings, the following is a normal machine cycle:

D1 is receiving signatures, and as its platform 110a descends it first closes normally open switch 257 to energize solenoid 160 to move clutch finger 164 to drive position, where it is picked up by drive finger 156 to move carriage D2 into loading position. As carriage D2 reaches the loading area with its platform 110 above the platform 110a, its platform latch 139 is released and opens normally closed switch 258 to deenergize solenoid 160 and hold the carriage in the loading area.

Platform 110a continues down, closing normally open switch 254 to energize solenoid 159a and move clutch finger 167a to drive position, where it is picked up by drive finger 156a to move carriage D1 to the unloading area. As D1 reaches the outward extremity of its travel, it opens normally closed switch 261, deenergizing solenoid 159a to hold the carriage in the unloading area.

With carriage D2 in the loading area, its platform 110 moves down until it closes normally open switch 256 to energize solenoid 160a and move clutch finger 164a to drive position, where it is picked up by drive finger 156a to return carriage D1 to the loading area. When D1 arrives at the loading area, its latch 139a is released and opens normally closed switch 260 to deenergize solenoid 160a and hold the carriage in the loading area.

Continuing downward movement of platform 110 brings it into closing contact with normally open switch 255 which energizes solenoid 159 and moves clutch finger 167 to drive position, where it is picked up by clutch drive finger 156 to return carriage D2 to the unloading area. At the end of its outward travel D2 opens normally closed switch 259 to deenergize solenoid 159 and hold D2 in the unloading area. This completes the cycle.

During the entire normal cycle as described above, the platform drive cam 131 and 131a operate continuously to cycle the platforms 110 and 110a, respectively, in timed relationship with the carriage travel. However, it sometimes happens that the feed of signatures to the receiving station is delayed, so the platform at loading position does not fill at its normal rate. When this occurs, the finger arm 221a (Fig. 9) is permitted to drop below its normal position, because its finger rests on top of the stack on the platform; and this causes finger lift 230a to close normally open switch 262, energizing solenoid 263 (Fig. 22) to disengage the single point clutch 52b and stop the platform drive E.

The timing of the shaft 52a (which acts through single point clutch 52b to drive the platforms), with respect

to the operation of control cam 233a which operates finger lift 230a, is such that although the movement of lift 230a away from the stack breaks the circuit to solenoid 263, the finger on lift 230a return to contact with the stack before the clutch 52b can re-engage. Thus, if the stack is still too low the lift 230a can again close switch 262 to actuate solenoid 263 and move clutch 52b to disengage position before the platform drive can resume.

Also on the control panel 250 is a normally closed manual platform clearing switch 264 which is in the circuit for retard switch 262. If the operator wishes to clear the platform with a small stack on it, for example at the end of a signature run, he may do so by opening switch 264 which deenergizes solenoid 263 and permits the platform drive to operate as though the stack were of normal size.

The remaining controls shown in Fig. 23 are the conventional ones for operating main drive clutch 36a and brake 36b, and will not be described.

In order to avoid the use of commutators for the rotary solenoids of the reversing carriage drive, their power wires, such as wire 268 in Figs. 2 and 4, are provided with slack and carried over pulleys 269 beneath infed C.

The foregoing detailed description is given for clearness of understanding only and no unnecessary limitations are to be understood therefrom, as modifications will be obvious to those skilled in the art.

We claim:

1. In a device of the character described: a frame; a signature receiving station on the frame at which signatures fed from a printing press may form a temporary pile; a pair of signature transfer platforms mounted for horizontal movement on the frame; selector means for locating said transfer platforms alternately in a loading area adjacent the receiving station, and in an unloading area; elevating means for raising and lowering said platforms in phased relationship with one another; delivery means for moving piles of signatures from the receiving station onto the platform in the loading area; first elevating control means for raising the platform in the unloading area substantially to the level of the receiving station; second elevating control means for progressively lowering the platform in the loading area as piles of signatures are moved onto it; and selector control means actuatable by the lowering of said platform in the loading area to trigger the selector means for reversing the locations of said two platforms when said platform in the loading area contains a predetermined load of signatures.

2. In a device of the character described: a frame; a signature receiving station on the frame provided with a movable stop against which signatures fed from a printing press may form a temporary pile; a plurality of signature transfer platforms movably mounted on the frame; selector means for locating one platform at a time in a loading area adjacent the receiving station; means for moving said stop periodically away from a temporary pile of signatures; a rockable delivery arm mounted on the frame which has movable gripping jaws; feed control means for rocking said arm toward the delivery station in timed relationship with movement of said stop away from a temporary pile of signatures in said station; jaw control means for moving said jaws into gripping engagement with a temporary pile of signatures for delivering said pile onto the loading transfer platform; and selector control means actuatable in conjunction with the rocking of said delivery arm to trigger the selector means for reversing the locations of said two platforms.

3. In a device of the character described: a frame; a signature receiving station on the frame at which signatures fed from a printing press may form a temporary pile; a pair of transfer carriages mounted for horizontal movement on the frame; selector means for locating said carriages alternately in a loading area adjacent the receiving station, and in an unloading area; a vertically reciprocable transfer platform on each carriage; elevating means

13

operatively connected with said transfer platforms for raising and lowering said platforms in phased relationship with one another; delivery means on the frame for moving piles of signatures from the receiving station onto the platform in the loading area; first elevating control means for raising the platform in the unloading area substantially to the level of the receiving station; second elevating control means for progressively lowering the platform in the loading area as piles of signatures are moved onto it; and selector control means actuatable by the lowering of said platform in the loading area to trigger the selector means for reversing the locations of said two platforms when said platform in the loading area contains a predetermined load of signatures.

4. In a device of the character described: a frame; a signature receiving station on the frame provided with a movable stop against which signatures fed from a printing press may form a temporary pile; a pair of transfer carriages mounted for horizontal movement on the frame; selector means for locating said carriages alternately in a loading area adjacent the receiving station, and in an unloading area; a vertically reciprocable transfer platform on each carriage; elevating means operatively connected with said transfer platforms for raising and lowering said platforms in phased relationship with one another; means for moving said stop periodically away from a temporary pile of signatures; a rockable delivery arm mounted on the frame which has movable gripping jaws; feed control means for rocking said arm toward the delivery station in time relation with movement of said stop away from a temporary pile of signatures in said station; a jaw control means for moving said jaws into gripping engagement with a temporary pile of signatures for delivering said pile onto the loading transfer platform; first elevating control means for raising the platform in the unloading area substantially to the level of the receiving station; second elevating control means for progressively lowering the platform in the loading area as piles of signatures are moved onto it; and selector control means actuatable by the lowering of said platform in the loading area to trigger the selector means for reversing the locations of said two platforms.

5. In a device of the character described: a frame; a signature receiving station on the frame at which signatures fed from a printing press may form a temporary pile; a pair of signature transfer platforms mounted for horizontal movement on the frame; selector means for locating said transfer platforms alternately in a loading area adjacent the receiving station, and in an unloading area; elevating means for raising and lowering said platforms in phased relationship with one another; delivery means for moving piles of signatures from the receiving station onto the platform in the loading area; first elevating control means for raising the platform in the unloading area substantially to the level of the receiving station; signature aligning means positioned alongside the loading area, said means including movable members adapted to jog signatures on a platform in said area into register; second elevating control means for progressively lowering the platform in the loading area as piles of signatures are moved onto it; and selector control means actuatable by the lowering of said platform in the loading area to trigger the selector means for reversing the locations of said two platforms when said platform in the loading area contains a predetermined load of signatures.

6. The device of claim 5 in which the signature transfer platforms are inclined laterally, the signature aligning means includes an upright longitudinal panel adjacent the low side of the platform, and the movable members urge the signatures against said panel.

7. The device of claim 6 in which the platforms have marginal recesses to facilitate manual removal of a stock of registered signatures therefrom at the unloading position.

8. In a device of the character described: a frame; a

14

signature receiving station on the frame at which signatures fed from a printing press may form a temporary pile; a pair of transfer carriages mounted for horizontal movement on the frame; selector means for locating said carriages alternately in a loading area adjacent the receiving station, and in an unloading area; a vertically reciprocable transfer platform on each carriage; elevating means operatively connected with said transfer platforms for raising and lowering said platforms in phased relationship with one another; delivery means on the frame for moving piles of signatures from the receiving station onto the platform in the loading area; first elevating control means for raising the platform in the unloading area substantially to the level of the receiving station; signature aligning

means positioned alongside the loading area, said means including movable members adapted to jog signatures on a platform in said area into register; second elevating control means for progressively lowering the platform in the loading area as piles of signatures are moved onto it; and selector control means actuatable by the lowering of said platform in the loading area to trigger the selector means for reversing the locations of said two platforms when said platform in the loading area contains a predetermined load of signatures.

9. The device of claim 8 in which the signature transfer platforms are inclined laterally, the signature aligning means includes an upright longitudinal panel adjacent the low side of the platform, and the movable members urge the signatures against said panel.

10. In a device of the character described: a frame; a signature receiving station on the frame at which signatures fed from a printing press may form a temporary pile; a pair of parallel longitudinal rails on the two sides of the frame below the level of the receiving station and extending from a loading area adjacent said station to an unloading area; a pair of rolling transfer carriages, one on each of said rails, each carriage having an upright frame member above the rail; a transfer platform mounted for vertical reciprocation on each said frame member, said transfer platforms extending cantilever-wise over the space between the rails; selector means for locating said carriages alternately in the loading area, and in the unloading area; elevating means operatively connected with said transfer platforms for raising and lowering said platforms in phased relationship with one another; delivery means on the frame for moving piles of signatures from the receiving station onto the platform in the loading area; first elevating control means for raising the platform in the unloading area substantially to the level of the receiving station; second elevating control means for progressively lowering the platform in the loading area as piles of signatures are moved onto it; and selector control means actuatable by the lowering of said platform in the loading area to trigger the selector means for reversing the locations of said two platforms.

11. The device of claim 10 in which the elevating means includes a separate pulley and cord system from which each transfer platform is suspended, a pair of pivotally connected links associated with each said system, one link being pivoted on the frame and the other on one of the transfer carriages, and pulleys on said links over which the cords of the associated system pass to eliminate slack in the cords as the carriage moves from one location to another.

12. In a device of the character described: a frame; a signature receiving station on the frame at which signatures fed from a printing press may form a temporary pile; a plurality of signature transfer platforms movably mounted on the frame; selector means for locating one platform at a time in a loading area adjacent the receiving station; delivery means for moving piles of signatures from the receiving station onto the platform in the loading area; and selector control means actuatable in conjunction with the operation of said delivery means to trigger the selector means for moving said platform out

of said area when it contains a predetermined load of signatures, and moving an empty platform into the area.

13. The device of claim 12 in which the transfer platforms are mounted on the frame for movement between an initial loading position substantially level with the receiving station, and a lower loaded position, and an empty platform moving into the loading area moves into position overlying the platform already in the area.

14. In a device of the character described: a frame; a signature receiving station on the frame provided with a movable stop against which signatures fed from a printing press may form a temporary pile; a pair of signature transfer platforms mounted for horizontal movement on the frame; selector means for locating said transfer platforms alternately in a loading area adjacent the receiving station, and in an unloading area; means for moving said stop periodically away from a temporary pile of signatures; a rockable delivery arm mounted on the frame which has movable gripping jaws; feed control means for rocking said arm toward the delivery station in timed relationship with movement of said stop away from a temporary pile of signatures in said station; jaw control means for moving said jaws into gripping engagement with a temporary pile of signatures for delivering said pile onto the loading transfer platform; elevating means for raising and lowering said platforms in phased relationship with one another; first elevating control means for raising the platform in the unloading area substantially to the level of the receiving station; second elevating control means for progressively lowering the platform in the loading area as piles of signatures are moved onto it; and selector control means actuatable by the lowering of said platform in the loading area to trigger the selector means for reversing the locations of said two platforms.

15. In a device of the character described: a frame; a signature receiving station on the frame at which signatures fed from a printing press may form a temporary pile; a pair of transfer carriages mounted for horizontal movement on the frame between a loading area adjacent the receiving station, and an unloading area; drive means on said frame; first solenoid clutch means to link the drive means selectively to said first carriage; second solenoid clutch means to link the drive means selectively to said second carriage; a vertically reciprocable transfer platform on each carriage; elevating means operatively connected with said transfer platforms for raising and lowering said platforms in phased relationship with one another; delivery means on the frame for moving piles of signatures from the receiving station onto the platform in the loading area; first elevating control means for raising the platform in the unloading area substantially to the level of the receiving station; second elevating control means for progressively lowering the platform in the loading area as piles of signatures are moved onto it; first selector control switch means actuated by the lowering of said platform in the loading area to engage one of said solenoid clutch means and move the carriage from the unloading area into the loading area; and second selector control switch means actuated by the lowering of said platform in the loading area to engage the other of said solenoid clutch means and move the lowered carriage into the unloading area.

16. In a device of the character described: a frame; a signature receiving station on the frame at which signatures fed from a printing press may form a temporary pile; a pair of signature transfer platforms mounted for horizontal movement on the frame; selector means for locating said transfer platforms alternately in a loading area adjacent the receiving station, and in an unloading area; elevating means for raising and lowering said platforms in phased relationship with one another; delivery means for moving piles of signatures from the receiving station onto the platform in the loading area; first elevating control means for raising the platform in

the unloading area substantially to the level of the receiving station; second elevating control means for progressively lowering the platform in the loading area as piles of signatures are moved onto it, said second control

5 means including means in said loading area to sense the vertical position of the top of the superposed signatures on the platform in the loading area with respect to the receiving station, and interrupter switch means actuatable by the movement of said sensing means below a predetermined point to interrupt the lowering of said platform; and selector control means actuatable by the lowering of said platform in the loading area to trigger the selector means for reversing the locations of said two platforms.

15. 17. In a device of the character described: a frame; a signature receiving station on the frame where signatures are formed into temporary stacks; a loading area adjacent said station; an unloading area more remote from the station; a plurality of movable platform means on said frame for transferring lifts of signatures from the loading area to the unloading area; means for moving said platforms between said areas; and stacker means for moving temporary stacks seriatim from the receiving station to a platform in the loading area, said stacker 20 means including a rocking stacker arm having movable gripping jaw means to grip a marginal portion of a temporary stack in the receiving station and move it from the station to a position above said platform; a reciprocating temporary stack support over which the 25 temporary stack is drawn by the stacker arm, and means for substantially simultaneously opening said jaws to release one end of the temporary stack and moving said support from beneath the opposite end of said stack.

18. In a device of the character described: a frame; a 35 signature receiving station in the frame where signatures are formed into temporary stacks; a platform adjacent said station upon which a series of temporary stacks are superimposed to form a lift of signatures; movable stacker means having movable gripping jaw means to grip a marginal portion of a temporary stack in the receiving 40 station and move it from the station to a position above said platform; a movable temporary stack support over which the temporary stack is drawn by the stacker means; and means for substantially simultaneously opening said 45 jaws to release one end of the temporary stack and moving said support from beneath the opposite end of said stack.

19. The device of claim 18 which includes jogger 50 means for jogging the signatures on the platform laterally with respect to the line of movement of the signature onto the platform, and in which means are provided to oscillate the temporary stack support after a temporary stack is released to jog the signatures longitudinally.

20. In a device of the character described: a frame; an 55 infeed on the frame for feeding signatures in shingled relationship; a signature receiving station in the frame to receive signatures from the infeed; retractable stop means in the receiving station against which said signatures abut to form a temporary stack; a platform adjacent said station upon which a series of temporary stacks are superimposed to form a lift of signatures; movable stacker means having movable gripping stacker 60 jaw means to grip a marginal portion of a temporary stack in the receiving station and move it onto said platform; brake means in the receiving station having a movable brake shoe to bear on signatures in the receiving station which are interleaved with those in the temporary stack but outside the grip of the stacker jaw means; and control means for retracting the stop means and moving the brake shoe into bearing contact with signatures in timed relationship with the gripping of a temporary stack by said jaws.

21. The device of claim 20 in which the receiving 70 station includes a brake anvil which extends above the

infeed in cooperative relationship to the movable brake shoe.

22. In a device of the character described: a frame; a signature receiving station in the frame where signatures are formed into temporary stacks with their folded edges at one side of the station; a platform adjacent said station upon which a series of temporary stacks are superimposed to form a lift of signatures; movable stacker means for transferring temporary stacks seriatim from the receiving station to the platform; stack jogging means adjacent the platform for jogging the signatures in each temporary stack into register with one another and with the signatures lower in the lift; stack control means adjacent the folded margins of the signatures on the platform, said stack control means including two sets of fingers which are separately movable between an engaged position and a free position; and cam means for moving said sets of fingers laterally and vertically in timed relationship with the operation of the stacker means and jogging means to compress the lift continuously as temporary stacks are added thereto.

23. The device of claim 22 in which the cam means includes rocking cams for swinging each set of fingers laterally in and out of engagement with the top of the lift, and lifting cams for raising each set of fingers above the lift of signatures when they are out of engagement, and said cams are timed to move the free set of fingers onto the top of the lift before the engaged set moves from beneath the last temporary stack.

24. The device of claim 22 in which the cam means is constructed and arranged to move the free set of fingers onto the top of the lift before the engaged set moves from beneath the last temporary stack.

25. In a device of the character described: a frame; a plurality of signature transfer platforms mounted on the frame for horizontal movement in and out of a loading area; selector means for locating one platform at a time in the loading area; means for delivering signatures to the platform in the loading area to form a load of signatures; and selector control means actuatable in conjunction with the operation of the delivery means to trigger the

18
selector means for moving said platform out of said area when it contains a predetermined load, and moving an empty platform into the area.

26. In a device of the character described: a frame; a plurality of signature transfer carriages mounted on the frame for horizontal movement in and out of a loading area; selector means for locating one carriage at a time in the loading area; a platform mounted on each carriage for vertical movement; means for delivering signatures to the platform in the loading area to form a load of signatures; means for lowering the platform in the loading area on its carriage as the load increases; and selector control means actuatable in conjunction with the operation of the delivery means to trigger the selector means for moving said carriage out of the loading area when its platform contains a predetermined load, and moving a carriage with an empty platform into the area.

27. In a device of the character described: a frame; a plurality of signature transfer platforms mounted on the frame for horizontal movement in and out of a loading area; means associated with each platform for moving it between an elevated loading position and a lower loaded position; selector means for locating one platform at a time in the loading area; means for delivering signatures to the platform at the loading area to form a load of signatures; means for lowering the platform in the loading area as the load increases; and selector control means actuatable in conjunction with the operation of the delivery means to trigger the selector means for moving an empty platform into the loading area at the elevated loading position above the loaded platform already in the area, and moving said loaded platform out of said area.
